(57) **CLAIM**

The ornamental design for a scraper spatula, as shown and described.

DESCRIPTION

FIG. 1 is an isometric view of the scraper spatula thereof.

FIG. 2 is a rear view thereof.

FIG. 3 is a front view thereof.

FIG. 4 is top view thereof.

FIG. 5 is bottom view thereof.

FIG. 6 is a left side view thereof.

FIG. 7 is a right side view thereof.

FIG. 8 is a front detail view showing contours thereof.

FIG. 9 is a rear detail view showing contours thereof.

FIG. 10 is a section surface view taken along line 10-10 of FIG. 2.

FIG. 11 is a section surface view taken along line 11-11 of FIG. 2.

FIG. 12 is an isometric view of a second embodiment of the scraper spatula thereof.

FIG. 13 is a rear view thereof.

FIG. 14 is a front view thereof.

FIG. 15 is a top view thereof.

FIG. 16 is a bottom view thereof.

FIG. 17 is a left side view thereof.

FIG. 18 is a right side view thereof.

FIG. 19 is a front detail view showing contours thereof.

FIG. 20 is a rear detail view showing contours thereof.

FIG. 21 is a section surface view taken along line 21-21 of FIG. 13; and,

FIG. 22 is a section surface view taken along line 22-22 of FIG. 13.

Any broken lines shown in the drawings are for illustrative purposes only and form no part of the claimed design.
